UNITED STATES PATENT OFFICE.

RASMUS MADSEN, OF HARTFORD, CONNECTICUT.

COMBINATION-TOOL.

No. 853,558.

Specification of Letters Patent.

Patented May 14, 1907.

Application filed February 23, 1907. Serial No. 358,808.

To all whom it may concern:

Be it known that I, RASMUS MADSEN, a subject of Denmark, residing at Hartford, in the county of Hartford, in the State of Connecticut, have invented certain new and useful Improvements in a Combination-Tool, of which the following is a specification.

My invention relates to a combination tool comprising a wrench and a series of screw drivers or other somewhat similarly shaped tool implements, and has for its special object the providing of a telescopic wrench, that is, a wrench in which the shank of the movable jaw is telescoped within the handle of the stationary jaw, with a telescopic tool-holder carrying a number of various size screw driver blades or other flat shanked tools, all of which may be inclosed within the holder and thus locked within the handle, and any one of which may be opened and locked into operative position when the tool is to be used as a screw driver or for the special use to which the projected blade is designed.

In the accompanying drawings illustrating my invention Figure 1 is a plan view of my improved wrench, the screw drivers or tool blades being closed. Fig. 2 is an end view of the same. Fig. 3 is a longitudinal section of the same, except that one of the screw drivers or tool blades is open. Fig. 4 is a plan view of the blade holder, and Fig. 5 is an end view of the same. Fig. 6 is an end view of the movable jaw of the wrench.

Similar letters of reference designate corresponding parts in all the figures.

The handle *b* of the wrench terminates at its left end in the stationary jaw *c* and at its right end in a cylindrical sleeve *d*. Telescoped within the handle, and sliding smoothly therein, is the shank *m* of the movable jaw *a*, said shank terminating in a screw *j*, which passes through a thumb nut *k* and is flattened at its inner end *i*. Said nut is shouldered in the aforesaid handle and its revolution causes the movable jaw to open or close. The cylindrical end *d* of the handle is provided with a smooth bore *o* in which is slidably fitted a cylindrical tool holder *n*. The right hand end of said holder is slotted, thereby forming two forks *t t'* between which are revolvably attached a number of screw driver blades. The blades are tapered to different widths and thicknesses on their outer ends, thereby forming different size screw drivers, and they are securely but rev-

olubly attached to said holder by means of a pin *e*, one end of which projects beyond the holder *n* into an L shaped lock-slot *f* cut on the outer edge of said cylindrical sleeve *d*. The left hand end of said holder is provided with a slot *h*, adapted to receive the flattened end *i* of the screw *j*, whereby the holder, when the wrench jaws are closed, may be locked against revolution. Between the bottom of bore *o* and the left hand end of the holder is a coiled spring *z* which tends to force the holder out of said bore, but which tendency is counteracted by the lock pin *e* resting against the side of the transverse portion of the L shaped lock slot.

The normal position of the wrench is that shown in Fig. 1, the jaw and blades being closed. If the tool is to be used as a wrench, the jaw *a* is opened by means of the thumb screw, thereby causing the jaw *a*, shank *m*, screw *j*, and flattened end *i* to take substantially the positions shown in dotted lines in Fig. 3. When the parts are in that position the pin *e*, resting against the right hand shoulder of lock-slot *f* overcomes the tendency of the spring *z* to eject the tool holder *n*, and it is thus retained in its proper position.

If the tool, being closed as in Fig. 1, is to be used as a screw driver, the thumb nut is revolved sufficiently far to withdraw the flattened end *i* of screw *j* from the slot *h* of holder *n*, thus permitting the holder to be revolved; the holder is then revolved until the pin *e* comes opposite the longitudinal portion of the lock-slot *f*, in which position the spring *z* will eject the holder from the handle. The desired screw driver blade is then revolved into the open position; the holder reinserted into the handle and revolved so that the pin *e* enters the transverse portion of the L shaped lock-slot, thereby locking it against the ejecting force of the coiled spring; and the nut is then revolved until the flattened end of the screw reenters the slot *h* of the holder, thereby locking the holder against revolution. The tool is then ready to be used as a screw driver, and a perfect alinement of the blade with the handle is maintained by reason of the narrow edge of its shank *x* exactly fitting the bore of the handle.

Having thus described my invention, I claim:

1. A combination-tool comprising a handle terminating at one end in a stationary

jaw and at the other end in a cylindrically bored sleeve having an L shaped lock-slot cut therein; a movable jaw having a threaded shank, terminating in a tongue, telescoped 5 within said handle; a thumb nut on said threaded shank; and a cylindrical tool holder slidably fitted within the bore of said handle, the inner end of which is slotted to receive said tongue of the movable jaw and thereby 10 lock the holder against revolution, and the outer end of which is slotted to form two forks between which are revolubly fastened, by means of a transverse pin which projects into said L shaped lock-slot and locks the 15 holder within said handle, a set of tools having flat shanks turned on their thin edges to exactly fit said bore of the handle, whereby each tool when in use is rigidly held in alignment with the handle.

20 2. A combination tool comprising a handle terminating at one end in a stationary jaw and at the other end in a cylindrically bored sleeve having an L shaped lock-slot cut therein; a movable jaw having a threaded shank, terminating in a tongue, telescoped 25 within said handle; a thumb nut on said threaded shank; a cylindrical tool holder slidably fitted within the bore of said handle, the inner end of which is slotted to receive 30 said tongue of the movable jaw and thereby lock the holder against revolution, and the outer end of which is slotted to form two forks between which are revolubly fastened, by means of a transverse pin which projects 35 into said L shaped lock-slot and locks the holder within said handle, a set of tools having flat shanks turned on their thin edges to exactly fit said bore of the handle, whereby

each tool when in use is rigidly held in alignment with the handle; and an ejection 40 spring between said holder and the bottom of the bore of said handle.

3. In a telescopic wrench of the class shown the combination with a bore o and slot f in the handle of the stationary jaw, and 45 a tongue i on the shank of the movable jaw, of a cylindrical tool holder slidably fitted within said bore and having a slot h at one end adapted to receive said tongue i and two tongues t t' at the other end between which 50 are revolubly attached, by means of a transverse pin e which projects into said lock-slot f, a set of tools having flat shanks turned on their thin edges to exactly fit said bore o.

4. In a telescopic wrench of the class 55 shown the combination with a bore o and a slot f in the handle of the stationary jaw, and a tongue i on the shank of the movable jaw, of a cylindrical tool holder slidably fitted within said bore and having a slot h at one 60 end adapted to receive said tongue i and two tongues t t' at the other end between which are revolubly attached, by means of a transverse pin e which projects into said lock-slot f, a set of tools having flat shanks turned on 65 their thin edges to exactly fit said bore, and a coiled spring z between the bottom of said bore of the handle and said holder.

In testimony whereof I have subscribed my name to this specification in the presence 70 of two subscribing witnesses.

RASMUS MADSEN.
